US00D837470S

(12) **United States Design Patent** (10) Patent No.: **US D837,470 S**
(45) Date of Patent: ** Jan. 1, 2019

(54) **SURFACE CLEANING HEAD WITH LEADING ROLLER**

(71) Applicant: **SHARKNINJA OPERATING LLC**,
Newton, MA (US)

(72) Inventors: **Gary V. Palladino**, Somerville, MA
(US); **Owen Rhys Alban Johnson**,
Needham, MA (US); **Junghwan Chei**,
Chestnut Hill, MA (US)

(73) Assignee: **SharkNinja Operating LLC**,
Needham, MA (US)

(**) Term: **15 Years**

(21) Appl. No.: **29/600,589**

(22) Filed: **Apr. 13, 2017**

Related U.S. Application Data

(63) Continuation of application No. 29/559,436, filed on
Mar. 28, 2016.

(57) **CLAIM**

The ornamental design of a surface cleaning head with
leading roller, as shown and described.

DESCRIPTION

FIG. 1 is a top perspective view of a surface cleaning head
with leading roller showing our new design;

FIG. 2 is a front view thereof;

FIG. 3 is a left side view thereof;

FIG. 4 is a right side view thereof; and,

FIG. 5 is a top view thereof.

The broken lines are included for the purpose of illustrating
the unclaimed portions of the article and form no part of the
claim.

1 Claim, 5 Drawing Sheets
